BOILER CONTROL APPARATUS

William S. Smoot, Highland Park, Ill., assignor
to Republic Flow Meters Company, Chicago,
Ill., a corporation of Illinois

Application July 8, 1950, Serial No. 172,701

10 Claims. (Cl. 236—245)

1

This invention relates to control apparatus for interrelated conditions and particularly to apparatus for controlling one condition or factor in response to a plurality of interrelated conditions affected by the first. Specifically the invention relates to control of the air supply to a steam generator in response to functions of steam pressure and flow.

The invention is particularly useful in the control of one element or factor which affects other interrelated conditions responding in different manner to changes in the first factor or to external conditions. This type of control is highly desirable in many industrial processes in addition to steam generators. Therefore, while the invention will be particularly described for controlling the supply of combustion air to a steam generator it is not intended to be limited to this purpose, this example being selected only for convenience of description of one application in which the invention has particular advantages.

It is one object of the invention to provide a control apparatus in which one of several interrelated conditions is controlled rapidly in response to a change in a second condition and more slowly in response to a change in a third condition. As applied to a steam generator the air flow is controlled rapidly in response to steam pressure and slowly in response to steam flow.

Another object is to provide control apparatus in which a rapid control effect in response to one condition is cancelled out gradually at the same time that another control effect responsive to another condition comes into effect.

Still another object is to provide a control apparatus in which the several control effects are provided by regulated fluid pressures, preferably pneumatic pressures.

A further object is to provide a controller including a fluid pressure responsive control device in which a time delay is produced by causing a liquid to flow through a restricted passage or orifice.

The above and other objects and advantages of the invention will be more readily apparent when read in connection with the accompanying drawings, in which—

Figure 1 is a diagrammatic view illustrating a boiler control apparatus embodying the invention;

Figure 2 is an enlarged section of the controller; and

Figure 3 is a view similar to Figure 1 showing an alternative control.

As shown in Figure 1, the control apparatus

of the present invention is applied to the control of air for combustion to a steam generator or boiler indicated generally at 10. Combustion air is supplied by a forced draft blower 11 and is controlled by a valve 12 in a conduit 13 connecting the blower to the boiler. Fuel is supplied through a conduit 14 to mix with the air in a combustible mixture, and the combustion products are exhausted through a flue 15 controlled in any desired manner by a valve 16. Steam generated in the boiler flows to any desired points of use through a main outlet pipe 17 and a steam header 18. The air valve 12 is controlled by a regulator 19 which may be of the type more particularly described and claimed in the patent to O'Connor, No. 2,039,924, and which is controlled through a balance beam 21 by two diaphragms 22 and 23. The diaphragm 22 is connected across an orifice 24 in the conduit 13 to measure the air flow, and the diaphragm 23 is supplied with fluid under pressure from a controller to be described more fully hereinafter. With this construction the regulator will control the valve 12 to maintain flow through the conduit 13 which is proportional to the pressure applied on the diaphragm 23.

The supply of fuel is similarly controlled by a regulator 25 connected to a valve 26 in the fuel line. The regulator 25 is controlled by a differential diaphragm 27 connected across an orifice in the fuel supply conduit 14 and a diaphragm 28 to which a controlling pressure is supplied as described hereinafter.

According to the present invention it is desired to maintain the air flow to the generator proportional to steam flow therefrom and to provide an initial correction of the air flow in response to changes in the steam pressure. This is because the fuel supply to the boiler will be controlled in response to steam pressure and it is desired initially to correlate changes in air flow with changes in fuel flow, both functions being responsive to steam pressure, so that upon an increase in steam demand the fuel supply and air flow will both increase proportionately in response to steam pressure. Later, when the steam demand has settled at a uniform value, the control of air flow will respond to steam flow only.

As shown, the header 18 is connected to a transmitter 29 which may be of the type more particularly described and claimed in the patent to Rosenberger, No. 2,431,200. This transmitter produces an air pressure in its outlet conduit 31 which is proportional to the existing steam pres-

sure. The conduit 31 is connected to the diaphragm 28 so that the fuel supply will be controlled in response to steam pressure and is also connected to the control indicated generally at 32 and more fully shown in Figure 2.

As illustrated in Figure 2 the controller comprises a balance beam 33 pivoted at its center and having a valve member 34 thereon which is moved toward and away from a bleed nozzle 35 as the beam moves. The bleed nozzle is supplied with air through a restriction 36 and is connected by a line 37 to the diaphragm 23 to supply a regulated air pressure thereto. The nozzle is also connected to a diaphragm 38 acting on a block 39 connected to the balance beam to urge the beam in one direction.

The beam is urged in the opposite direction by a similar diaphragm 41 which is connected to the line 31 to receive a pressure from the transmitter 29 which is proportional to the steam pressure. The diaphragm 41 acts on a block 42 on the opposite side of the beam pivot from the block 39 so that it tends to turn the beam in the opposite direction from the diaphragm 38.

The line 31 is also connected to a time delay pressure responsive device 43 acting on the beam 42 in opposition to the diaphragm 41. The device 43, as shown, comprises a vertical cylindrical casing 44 closed at its bottom by a diaphragm 45 acting on the block 42. An intermediate partition 46 in the casing 44 separates it into an upper chamber 47 and a lower chamber 48, one side of which is closed by the diaphragm 45. The lower parts of the chambers 47 and 48 are connected by a tube 49 which is variably restricted by a valve member 51 adjustably threaded in the top of the casing. The pipe 31 connects to the upper part of the chamber 47.

The casing is adapted to contain a body of liquid 52, a part of which will normally be in the upper chamber 47 and the remainder of which will be in the lower chamber 48. The pipe 49 extends below the liquid level in the lower chamber so that upon changes in the relative pressures in the two chambers liquid will be caused to flow from one to the other at a rate determined by the setting of the valve 51.

A similar time delay unit 53 is provided acting on the block 39 in opposition to the diaphragm 38 and its upper chamber is supplied with a regulated air pressure through a conduit 54 from a transmitter 55 similar to the transmitter 29. The transmitter 53 is connected across an orifice 56 in the steam outlet conduit 17 so that its transmitted pressure will be proportional to steam flow from the generator.

In operation of the system assuming a sudden increase in the demand for steam, the pressure in the header 18 will drop and the flow of steam will tend to increase. The immediate effect will be a decreased pressure of steam effecting the transmitter 29 so that its output pressure through the line 31 will increase. This increased pressure acting on the diaphragm 28 will operate the regulator 25 to increase the flow of fuel. At the same time it will increase the pressure on the diaphragm 41 tending to rock the beam 33 clockwise so that the pressure behind the nozzle 35 will increase proportionately to rebalance the beam through the diaphragm 38. This increased pressure will also be transmitted to the diaphragm 23 to cause the regulator 19 to open valve 12 thereby to effect an immediate increase in air flow. The increased pressure from transmitter 29 acting on the liquid in the upper chamber 47

will gradually force liquid from this chamber into the lower chamber 48 gradually to build up the pressure on the diaphragm 41 and completely cancels the effect of steam pressure on the controller. At the same time, a similar action will occur in the time delay device 53 to produce a pressure opposing the diaphragm 38 which is proportional to steam flow. By the time steam pressure effect on the control has been cancelled the full steam flow effect will be present so that the pressure produced behind the nozzle 35 to rebalance the beam 33 will be proportional to a function of steam flow and the air flow will be controlled to be proportional to steam flow. In this way an initial correction is made in response to steam pressure, and this effect will gradually be cancelled to be replaced by an effect responsive to steam flow. In this way a rapid and extremely accurate control of the air flow is produced in the manner desired.

Similar controls of other industrial processes are contemplated such that the initial change will be responsive to one factor or condition and will subsequently be replaced by a control responsive to another factor or condition. Figure 3 illustrates one such alternative control applied to a steam generator in which both the fuel and air are controlled in response to steam pressure and an initial adjustment is made in response to steam flow. Parts in Figure 3 corresponding to like parts in Figures 1 and 2 are designated by the same reference numerals plus 100.

In this construction the loading diaphragms 123 and 128 of the air flow regulator 119 and the steam flow regulator 125 are both connected to the line 137 to be simultaneously controlled in response to the pressure produced back of the nozzle 135. The pressure responsive transmitter 129 is connected to the pressure responsive device 153 and the flow responsive transmitter is connected to the two devices 141 and 143.

With this construction both the fuel and air are normally controlled in response to steam pressure so that the steam pressure will tend to be held constant. Upon a change in demand the change in steam flow will immediately affect the device 141 to change the rates of fuel and air supply. The steam flow effect will gradually be cancelled through the device 143 so that control of the fuel and air will return to a response to steam pressure.

In both of the constructions shown the primary control is responsive to the value of one factor and is modified in response to the rate of change of another factor. Thus in Figure 1 as long as steam pressure remains constant the control is solely in response to steam flow and steam pressure produces an effect only during a change, the effect being proportional to the amount and rate of change. Similarly in Figure 2 the control is solely responsive to steam pressure except during a change in the rate of steam flow.

This same principle can obviously be applied to the control of other types of apparatus or processes and it is not intended that the invention shall be limited to the illustrative embodiments shown nor otherwise than by the terms of the appended claims.

What is claimed is:

1. Control apparatus for interrelated conditions comprising a balance beam, means for producing a force proportional to one of said

conditions, a pair of force responsive devices responsive to said force, and acting in opposite directions on the balance beam, means to introduce a time delay into the response of one of said devices, means to produce a second force responsive to a second of said conditions, a force responsive device responsive to the second force to urge the beam in one direction, means to introduce a time delay into the response of the last named device, means responsive to unbalance of the beam to produce a third force, a force responsive device responsive to the third force acting on the beam to balance it, and control means responsive to the third force to control a factor affecting said conditions.

2. Control apparatus for interrelated conditions comprising a balance beam, an instrument responsive to one of said conditions to produce a fluid pressure proportional to the condition, a pair of pressure responsive devices responsive to the fluid pressure and acting in opposite directions on the beam, means including a variable restriction to introduce a time delay into the response of one of said devices to changes in the fluid pressure, a second instrument responsive to a second of said conditions to produce a second fluid pressure, a pressure responsive device responsive to the second fluid pressure to urge the beam in one direction, means including a variable restriction to introduce a time delay into the response of the last named device to changes in the second fluid pressure, means responsive to unbalance of the beam to produce a third fluid pressure, a pressure responsive device responsive to the third fluid pressure acting on the beam in opposition to the last named device, and control means responsive to the third fluid pressure to control a factor affecting said conditions.

3. Control apparatus for a steam generator having an air supply connection and a steam outlet connection comprising control means for the air supply, a controller for the control means, an operating element in the controller connected to the steam outlet connection and instantaneously responsive to steam pressure, delayed action means in the controller gradually to cancel the effect of the first named means, and a delayed action operating element in the controller responsive to steam flow to operate the control means and thereby vary the air supply.

4. Control apparatus for a steam generator having an air supply connection and a steam outlet connection comprising control means for the air supply, a controller for the control means, means for producing a force proportional to steam pressure, a pair of force responsive devices in the controller acting in opposite directions thereon and responsive to said force, means to introduce a time delay into the response of one of said devices, means to produce a force responsive to steam flow, and a delayed action device in the controller connected to the last named means to respond to the last named force and operating the controller to vary the air supply.

5. Control apparatus for a steam generator having an air supply connection and a steam outlet connection, control means for the air supply, an instrument responsive to the steam pressure in the outlet connection to produce a fluid pressure, a controller including a balance beam, a pair of pressure responsive devices responsive to said fluid pressure and acting in opposite directions on the balance beam, means including a variable restriction to delay the response of one

of said devices to changes in fluid pressure, a second instrument responsive to steam flow through the outlet connection to produce a second fluid pressure, a pressure responsive device responsive to the second fluid pressure and acting on the balance beam, and means responsive to unbalance of the balance beam to operate the control means thereby to control the air supply.

6. Control apparatus for a steam generator having an air supply connection and a steam outlet connection, control means for the air supply, an instrument responsive to the steam pressure in the outlet connection to produce a fluid pressure, a controller including a balance beam, a pair of pressure responsive devices responsive to said fluid pressure and acting in opposite directions on the balance beam, means including a variable restriction to delay the response of one of said devices to changes in fluid pressure, a second instrument responsive to steam flow through the outlet connection to produce a second fluid pressure, a pressure responsive device responsive to the second fluid pressure and acting on the balance beam, means responsive to unbalance of the balance beam to produce a third fluid pressure, a pressure responsive device responsive to the third fluid pressure and acting on the balance beam to rebalance it, and means responsive to the third fluid pressure to operate the control means thereby to control the air supply.

7. In a control apparatus, a controller comprising a balance beam, at least three fluid pressure responsive devices acting on the beam, each of two of said devices acting in opposite directions on the beam comprising a vertically elongated housing, a diaphragm closing one end of the housing and acting on the beam, a partition in the housing dividing it into two vertically spaced chambers adapted to contain a liquid, a conduit connecting the lower parts of the chambers, a valve variably to restrict the conduit, a fluid pressure connection to the chamber remote from the diaphragm, the third device including a diaphragm, and a substantially unrestricted fluid pressure connection to the last named diaphragm.

8. Control apparatus for a steam generator having an air supply connection, a fuel supply connection and a steam outlet connection comprising devices respectively responsive to steam pressure in and steam flow through the outlet connection to produce forces, and control means for the air and fuel supplies responsive to one of the forces and to the rate of change of the other.

9. Control apparatus for a steam generator having an air supply connection, a fuel supply connection and a steam outlet connection comprising devices respectively responsive to steam pressure in and steam flow through the outlet connection to produce forces, and control means for the air and fuel supplies responsive to one of the forces and to the rate of change of the other, and means to introduce a time delay into the response of the control means to said one of the forces.

10. Control apparatus for interrelated conditions comprising a balance beam, first and second means for producing forces responsive to two of said conditions respectively, a force responsive device connected to one of said means and substantially instantaneously responsive to the force produced thereby to urge the beam in one direction, a pair of vertically elongated housings, dia-

diaphragms closing the lower ends of the housings and connected to spaced points on the beam to urge it in opposite directions in response to pressure on the diaphragms, a partition in each of the housings dividing it into spaced chambers adapted to contain a liquid and one of which is closed by the diaphragm, means forming restricted passages connecting the lower parts of the chambers in each housing, connections from the first and second means to the other chambers of the housings respectively to supply fluid pressures thereto proportional to said two of the conditions, and means responsive to unbalance of the beam to control a third of the conditions.
